UNITED STATES PATENT OFFICE.

SEBASTIAN DIETRICH, OF CUDAHY, WISCONSIN.

TAKE-OFF MECHANISM FOR RUBBER-MIXING MILLS.

1,364,183.

Specification of Letters Patent. Patented Jan. 4, 1921.

Application filed April 4, 1918. Serial No. 226,626.

To all whom it may concern:

Be it known that I, SEBASTIAN DIETRICH, a citizen of the United States, residing at Cudahy, in the county of Milwaukee, State 5 of Wisconsin, have invented certain new and useful Improvements in Take-Off Mechanism for Rubber-Mixing Mills, of which I declare the following to be a full, clear, and exact description.

10 This invention relates to an automatic take-off mechanism for rubber mixing mills.

The principal object of this invention is to provide an automatic mechanism for taking mixed stock off of rubber mixing mills.

15 A further object of my invention is to provide such a mechanism which will take the mixed stock off of the mixing mill in a strip of uniform width.

Another object of my invention is to provide 20 an automatic mechanism for taking the mixed stock off of a mixing mill, such mechanism being provided with automatic means for dusting soap stone or similar powder upon the stock as it is taken off of the mill.

25 Further objects, and objects relating to economies of manufacture and details of construction, will definitely appear from the detailed description to follow.

I accomplish the objects of my invention 30 by the devices and means described in the following specification. My invention is clearly defined and pointed out in the appended claims.

A structure constituting a preferred embodiment of my invention is illustrated in 35 the accompanying drawing, forming a part of this specification, in which:

Figure I is a top plan view showing a portion of a rubber mixing mill with a take-off mechanism embodying my invention connected thereto.

Fig. II is a sectional view taken on the line II—II of Fig. I and showing the take-off mechanism in side elevation.

45 Fig. III is a fragmentary, detail, sectional view taken substantially on the line III—III of Fig. I.

Fig. IV is an enlarged view of the upper end of Fig. II, the conveying belt not being 50 shown.

Fig. V is a detail, sectional view, taken substantially on the line V—V of Fig. III, and,

Fig. VI is a fragmentary, detail, sectional view taken substantially on the line VI—VI 55 of Fig. V.

In the drawings, similar reference numerals refer to similar parts throughout the several views, and the sectional views are taken looking in the direction of the little arrows at 60 the ends of the section lines.

In rubber mixing mills there are provided, customarily, a pair of squeeze rolls 11 and 12 which are driven in opposite directions and suitably journaled in the mill frame 10. 65 The ingredients of the batch to be mixed are dumped between the squeeze rolls and are thoroughly mixed by the action of the squeeze rolls, as they carry a thin sheet of the mixed stock around between the rolls, 70 which sheet adheres to the surface of the rolls so as to form a sheet of stock coating the squeeze rolls. This sheet of stock is repeatedly removed from the rolls and rolled up into a bundle and dumped between the 75 squeeze rolls once more to repeat the process until the batch is thoroughly mixed and the mixed stock is ready to be removed from the rolls of the mixing mill on which it is carried in a sheet adhering to the rolls. 80

Heretofore, it has been the practice for the operator to manually sever a strip of approximately the desired width by the use of a knife and for his assistant to pull the continuous strip from the roll by hand into 85 a suitable container which receives the strip, dusting the strip with powdered soap stone, as he does this, in order to prevent portions of the rubber strip adhering to each other. The result is that the strip removed varies 90 in width, as the operator does not always apply his knife at the same point to the roll. A strip of this nature is usually sent from the mixing mills to the tubing mills through which it is fed and the variation 95 in width of the strip sometimes causes the tubing mill to choke and interferes with its operation.

By my invention, I have provided an automatic mechanism for removing this 100 strip from the rolls, such mechanism insuring a strip of uniform width and at the same time automatically dusting powdered soap stone on the strip as it drops into a container waiting to receive it. This mechanism eliminates the necessity for an assistant 105

or helper as its operation is entirely automatic.

A post 13 projects from the side of the mill frame 10 and an arm 14 is provided with a portion 15 bent back upon itself and embracing the post 13. Bolts 16 draw the portion 15 toward the arm 14 so as to clamp the arm to the post 13. The arm 14 extends upwardly and laterally from the post 13 and carries at its upper end a laterally projecting pin or bolt 17 on which the bar 18 is pivotally mounted. At the end of the bar 18 adjacent the squeeze roll 12 it carries the laterally projecting shaft 19 on which the pulley 20 is journaled. At substantially an equal distance from the other side of the pin 17, the bar 18 carries another laterally extending shaft 21 on which the pulley 22 is journaled. The shafts 19 and 21 are held in position relative to the bar 18 by means of the nuts 28 and 23 threaded thereon. An endless conveyer belt 24 runs over the pulleys 20 and 22.

Straps 25 are secured to the bar 18 between the pulleys 20 and 22 and extend transversely to the bar. These straps carry at their upper ends, the platform 26 which extends beneath the upper reach of the endless conveyer belt 24 and is wider than said belt, being provided with upwardly extending guide flanges 27 at each side thereof.

At the extreme upper end of the bar 18 there is carried a bolt or pin 29 on which the bar 30 is pivoted. This bar forms one side member of the frame 31 of a box having a bottom 32 of wire screening. One of the forward corners of the frame 31 has secured thereto a leg 33 which extends downwardly below the bottom of said box. A tripper cam 34 is riveted to one edge of the flange of pulley 22 by the rivets 35, in position to engage the lower end of the leg 33.

The post 13 is provided with a longitudinally extending keyway 44 and a pair of knife holders 36 are mounted on said shaft, each of said knife holders having a key 45 fitting in said keyway 44 so as to prevent rotation of the knife holders relative to the post 13. A series of holes or notches 46 are provided in the post 13 in positions so that any one of them may be engaged by the set screw 37 carried by the knife holder so as to accurately position the knife holder relative to the post 13. Each knife holder is provided with a slot 38 in its upper part, in which a thin knife 39 is disposed. Said knife has a bayonet slot 40, opening downwardly, in which a pin 41, extending transversely of the knife holder 36 across the slot 38, is engaged. The point 42 of the knife contacts with the roll 12 so that the cutting edge of the knife slits the stock on the roll. A spring 43 is connected at one end to the post 13 and at the other end to

the shaft 19 and pulls the bar 18 on its pivot so as to hold the pulley 20 in contact with the roll 12.

From the description of the parts given above, the operation of this mechanism should be very readily understood. The squeeze rolls 11 and 12 are positively driven in opposite directions, the direction of rotation being indicated by arrows on the various figures of the drawings. The rotation of the roll 12 drives the pulley 20, due to the frictional engagement between the two, so that the belt 24 is driven in the direction indicated by the arrow in Fig. II. The knife holders 36 are positioned on the post 13 by means of the set screws 37 so as to be spaced at a pre-determined distance, depending upon the width of the strip which the operator desires to take from the stock A on the mixing mill. The point 42 of each knife engages the stock A on the roll 12 at a point just above the end of the horizontal diameter of said roll and slits the stock A in parallel slits, forming a strip B of uniform width. This strip B adheres to the conveyer belt 24 and is carried by said belt up over the platform 26 and the pulley 22 and drops from the pulley 22 into a container which is provided to receive it. Spring 43 holds the pulley 20 under tension against the roll.

As the pulley 22 revolves, the tripper cam 34 strikes the leg 33 once every revolution and lifts it, as shown in dotted lines in Fig. IV, allowing it to drop suddenly. This jars the powdered soap stone contained in the box 31 and dusts some of it through the screening 32 forming the bottom of the box upon the strip of rubber B which is being fed over the belt 24. When the mechanism is not in use, the knives and knife holders can be removed by releasing the set screws 37 and sliding the knives laterally on the post 13. The bar 18 can then be swung on its pivot so as to carry the pulley 20 upwardly away from the roll 12 and the mechanism can be held in this position or it can be entirely removed from the post 13 by releasing the bolts 16 which clamp the arm 14 to the post.

It will be observed that this mechanism is fixed relative to the squeeze rolls and in order to provide a continuous feed of the stock through this take-off mechanism, the operator continuously removes portions of the rubber stock from other parts of the squeeze rolls and dumps them between the squeeze rolls in line with the knives so that a sheet of stock is continuously formed on the squeeze roll at this point. This operation is continuous until all of the stock has been removed from the mixing mills.

I am aware that the particular embodiment of my invention, which I have here shown and described, is susceptible of con-

siderable variation without departing from the spirit thereof, and therefore, I desire to claim my invention broadly, as well as specifically, as indicated by the appended 5 claims.

Having thus described my invention, what I claim as new and desire to secure by Letters Patent, is:

1. The combination with a rubber mixing mill, of means for slitting the stock on said mill in parallel lines; automatic means for taking off the strip of stock so formed; and automatically operable means for dusting a suitable powder on said strip. 10
2. The combination with a rubber mixing mill, of means for slitting the stock on said mill in parallel lines; and take-off mechanism contacting with one of the rolls, and automatically operable thereby to take 15 off the strip of stock so formed.
3. The combination with a rubber mixing mill, of means for slitting the stock on said mill in parallel lines; means driven by said mill, and automatically operable to take 20 off the strip of stock so formed; and automatic means for dusting a suitable powder on said strip.
4. The combination with a rubber mixing mill, comprising a pair of squeeze rolls 30 oppositely driven; of means for slitting the stock on one of said rolls in parallel lines; and an automatic take-off mechanism, including a pulley contacting with and driven by one of said rolls and operable to automatically take off the strip of stock formed by said slits.
5. The combination with a rubber mixing mill including a pair of positively driven squeeze rolls; of means for slitting 40 the stock on one of said rolls in parallel lines; automatic take-off mechanism, including a pulley contacting with and driven by one of said rolls, said take-off mechanism being operable to remove the strip of stock 45 formed by said slits, and automatic means operable to dust the strip of stock so formed with a suitable powder.
6. The combination with a rubber mixing mill, including a mill frame, and a pair 50 of positively driven squeeze rolls; of a support carried by said mill frame; a frame member carried by said support; a pulley journaled at one end of said frame member and contacting with one of said squeeze 55 rolls; a pulley journaled at the opposite end of said frame member; an endless belt passing around said pulleys and between the first-mentioned pulley and the squeeze roll; and means for slitting the stock on said 60 squeeze roll in parallel lines.
7. The combination with a rubber mixing mill, including a mill frame and a pair of positively driven squeeze rolls; of a frame member supported from said mill 65 frame; a pulley journaled in one end of said frame member and contacting with one of said squeeze rolls; a pulley journaled on the other end of said frame member; an endless conveyer belt passing over said pulleys and between said first mentioned pulley and the squeeze roll. means for slitting the stock on said roll in parallel lines; and automatic means for dusting a suitable powder on the strip of stock so formed. 70
8. The combination with a rubber mixing mill, including a pair of positively driven squeeze rolls and a mill frame; of a support extending from said mill frame; a pair of knives carried by said support and operable to slit the stock on one of said squeeze rolls in parallel lines to form a strip of stock; and a take-off mechanism including a pulley contacting with and driven by said squeeze roll and automatically operable to remove the strip so formed from the roll. 75
9. The combination with a rubber mixing mill, including a pair of positively driven squeeze rolls and a mill frame; of a support extending from said mill frame; a pair of knives carried by said support and operable to slit the stock on one of said squeeze rolls in parallel lines to form a strip of stock; a take-off mechanism driven by said squeeze roll and automatically operable to remove the strip so formed from the roll; and automatic means for dusting the strip so formed with a suitable powder. 80
10. The combination with a rubber mixing mill, including a mill frame and a pair of positively driven squeeze rolls; of a support extending from said mill frame; a pair of knives carried by said support and operable to slit the stock on one of said squeeze rolls in parallel lines to form a strip of stock; a frame member carried by said support above said knives; a pulley journaled in one end of said frame member and contacting with said squeeze roll; a pulley journaled at the other end of said frame member; and an endless conveyer belt passing around said pulleys and between said first mentioned pulley and the squeeze roll, and operable to remove said strip of stock from the squeeze roll to said belt. 100
11. The combination with a rubber mixing mill including a mill frame and a pair of positively driven squeeze rolls; of a support extending from said mill frame; a pair of knives carried by said support and operable to slit the stock on one of said squeeze rolls in parallel lines to form a strip of stock; a frame member carried by said support above said knives; a pulley journaled in one end of said frame member and contacting with said squeeze roll; a pulley journaled at the other end of said frame member; an endless conveyer belt passing around said pulleys and between said first men- 115
12. The combination with a rubber mixing mill including a mill frame and a pair of positively driven squeeze rolls; of a support extending from said mill frame; a pair of knives carried by said support and operable to slit the stock on one of said squeeze rolls in parallel lines to form a strip of stock; a frame member carried by said support above said knives; a pulley journaled in one end of said frame member and contacting with said squeeze roll; a pulley journaled at the other end of said frame member; an endless conveyer belt passing around said pulleys and between said first men- 120
13. The combination with a rubber mixing mill including a mill frame and a pair of positively driven squeeze rolls; of a support extending from said mill frame; a pair of knives carried by said support and operable to slit the stock on one of said squeeze rolls in parallel lines to form a strip of stock; a frame member carried by said support above said knives; a pulley journaled in one end of said frame member and contacting with said squeeze roll; a pulley journaled at the other end of said frame member; an endless conveyer belt passing around said pulleys and between said first men- 125

- tioned pulley and the squeeze roll, and operable to remove said strip of stock from the squeeze roll to said belt; and automatic means for dusting a suitable powder on said strip of stock.
12. The combination with a rubber mixing mill, including a mill frame and a pair of positively driven squeeze rolls; of a support extending from said mill frame; a pair 10 of knives carried by said support and engaging one of said squeeze rolls to slit the stock thereon in parallel lines to form a strip of stock; a frame member carried by said support above said knives; a pair of pulleys journaled on said frame member; one of said pulleys contacting with said squeeze roll; an endless conveyer belt passing over said pulleys and between one of them and the adjacent squeeze roll; and automatic 15 means operable by the other of said pulleys to dust a suitable powder on the strip of stock.
13. The combination with a rubber mixing mill, including a mill frame and a pair 20 of positively driven squeeze rolls; of a support extending from said mill frame; a pair of knives carried by said support and contacting with one of said squeeze rolls to slit the stock thereon in parallel lines to form a strip of stock; a frame member carried by 25 said support above said knives; a pair of pulleys journaled on said frame member; one of said pulleys contacting with said squeeze roll, an endless conveyer belt passing around said pulleys and between one of them and the adjacent squeeze roll; a box pivotally mounted on said frame member and provided with a perforate bottom; and 30 a leg depending from said box; and a tripper cam mounted on one of said pulleys and engaging said leg.
14. The combination with a rubber mixing mill, including a mill frame and a pair 35 of positively driven squeeze rolls; of a support extending from said mill frame; means for slitting the stock on one of said squeeze 40 rolls to form a strip of stock; a frame member carried by said support; pulleys journaled on said frame member, one of said pulleys contacting with said squeeze roll; an endless conveyer belt passing around said 45 pulleys and between one of them and the adjacent squeeze roll; a box pivotally mounted on said frame member and provided with a perforate bottom; a leg depending from said box; and a tripper cam mounted on one 50 of said pulleys and engaging said leg.
15. The combination with a rubber mixing mill, including a mill frame and a pair 55 of positively driven squeeze rolls; of a support extending from said mill frame; means for slitting the stock on one of said squeeze 60 rolls in parallel lines to form a strip of stock; a frame member carried by said support; a pair of pulleys journaled on said frame member, one of said pulleys contact- 65 ing with said squeeze roll, an endless conveyer belt passing around said pulleys and between one of them and the adjacent squeeze roll; and a platform provided with marginal flanges disposed beneath the upper 70 reach of said conveyer belt between said pulleys.

In testimony whereof, I affix my signature.

SEBASTIAN DIETRICH.
